UNITED STATES PATENT OFFICE.

RICHARD H. WESTERFIELD, OF KENTON, OHIO.

DESIGN FOR A RANGE.

SPECIFICATION forming part of Design No. 35,988, dated August 5, 1902.

Application filed June 6, 1902. Serial No. 110,555. Term of patent 3½ years.

To all whom it may concern:

Be it known that I, RICHARD H. WESTERFIELD, a citizen of the United States, residing at Kenton, in the county of Hardin and State of Ohio, have invented and produced a new, original, and ornamental Design for Ranges, of which the following is a specification, reference being had to the accompanying drawing, forming part thereof.

10 The figure is a perspective view of a range, showing my new design.

As shown in the drawing, the leading or material feature of my design consists in ornamental surfaces formed on the several parts 15 of the range, said surface having thereon the approximately circular foliations of various

sizes. Said specially-formed foliations are applied to base 2, to the shelves 3 and 4, to the several doors, and to the extension 5 in the manner illustrated.

Having described my invention, what I claim as new, and desire to secure by Letters Patent, is—

The ornamental design for a range, as herein shown and described.

In testimony whereof I have signed my name to this specification in the presence of two subscribing witnesses.

R. H. WESTERFIELD.
